ANTONIO L. MORA, OF NEW YORK, N. Y.

Letters Patent No. 80,200, dated July 21, 1868.

IMPROVED BUREAU-TRUNK.

The Schedule referred to in these Letters Patent and making part of the same.

TO ALL WHOM IT MAY CONCERN:

Be it known that I, ANTONIO L. MORA, of the city, county, and State of New York, have invented a new and improved Bureau-Trunk; and I do hereby declare that the following is a full, clear, and exact description thereof, which will enable others skilled in the art to make and use the same, reference being had to the accompanying drawings, forming part of this specification.

This invention relates to a new and improved method of constructing trunks for travelling purposes, or for keeping wearing-apparel, papers, jewels, and other valuables, whereby the same are rendered much more useful and convenient than they have heretofore been; and the invention consists in combining the ordinary trunk, as hitherto used, with the convenient chamber-bureau, thus securing the advantages of both in a portable form, as will be hereinafter more fully described.

To illustrate the advantages and value of my invention, the drawings are made to represent the bureau-trunk in the various positions it would assume in being used.

Figure 1 represents the trunk as when closed or locked up, in which condition it presents the appearance of the ordinary travelling-trunk.

Figure 2 represents it with the cover raised or thrown back.

Figure 3 is a view of the upper portion or top of the trunk when the cover is raised, as in fig. 2.

Figure 4 (sheet 2) represents the trunk with the cover closed, and with the front of the trunk opened, exposing the body of the trunk in the form of a bureau.

Figure 5 represents the trunk with both the cover and front open.

Figure 6 shows the front or bureau part in a modified form, or as it may be made for keeping books, papers, or jewelry, which form is designed to accommodate a class of merchants who travel with valuable articles of merchandise, as samples or otherwise.

Similar letters of reference indicate corresponding parts.

A represents the cover or lid of the trunk. This cover may be attached to the body of the trunk by the ordinary butt-hinge, or by my improved adjustable ratchet-hinge, for which I have an application for a patent now pending.

B B represent the front or doors of the trunk, which is formed of two or more parts or doors, which are hinged to the ends of the trunk, as seen in the drawing at C.

Should the front be formed of more than two parts, they may be hinged together in any convenient manner, and when so formed, or when formed of one single piece or door, the front may be hinged to one side or end and locked at the other, or there may be vertical stationary pieces permanently attached to the body of the trunk, on each side, or at each of the front corners, with the door or doors between. But when there are drawers arranged, as represented in the drawing, the latter formation would be impracticable.

As this trunk is constructed, and as seen in fig. 2, the front is securely locked, while the cover is open; and as seen in fig. 4, the cover is locked while the front is open, so that access may be had to either part without exposing or disturbing the other.

For the preservation or transportation of articles of clothing, (especially for ladies,) the advantages of the arrangement shown cannot be too highly estimated.

As trunks have been hitherto made and used, the body of the trunk, when packed, (with the exception, perhaps, of what may be contained in one tray, in the top part of the trunk,) presents a promiscuous heap of articles pressed out of all shape, which, when a single article is wanted, have to be removed one by one, rumpled and wrinkled, and unfit for use. When the article is found, (if a lady's dress, or almost any other article belonging to a lady's wardrobe,) the services of the laundress are at once required.

To enable ladies as well as gentlemen to travel and preserve their clothing in a wearable condition is my principal object in this invention, and in combining the bureau with the trunk the object is accomplished.

Articles of the finest linen, or laces of the finest texture, when prepared for the wearer in the most delicate manner, may be preserved uninjured in these drawers for weeks, whether in travelling or elsewhere.

As before stated, the arrangements of the bureau may be varied to suit the various uses for which the trunk is intended.

The drawers and pigeon-holes may vary in size or number, as may be desired.

When the front of the trunk (or the bureau) is closed, the projecting flange or band of the cover closes over the doors of the front, as seen in fig. 1, thus securely holding them in that position. But, in addition to this fastening, there are bolts connected with the lock of the trunk, on the inside, which are operated by the key as the trunk is locked, the ends of which bolts enter recesses in the bottom of the trunk, so that when the trunk is locked, the doors are firmly secured at top and bottom.

The lock which I use on this trunk is of peculiar construction, for which I am about making application for Letters Patent. Suffice it to say, in this connection, that the cover of the trunk and the front or doors of the bureau are securely fastened, either separately or together, with one key, operating in one key-hole.

I do not confine myself to any particular form or proportion of frame for the bureau-trunk, nor to the method of binding or protecting the same, nor do I confine myself to a bureau-trunk with a cover or lid, as the same may be made without any opening by or at the top of the trunk.

Having thus described my invention, what I claim as new, and desire to secure by Letters Patent, is—

The bureau-trunk, constructed as described, its top, A, being hinged at its back to the body of the trunk, and provided with interior compartments and a flange around its lower edge, when the doors B, which cover the drawers, are hinged to the front sides of the ends of the trunk, and are held closed by the flange of the cover; which said cover is locked at two points by means of one lock, all arranged as described, for the purpose specified.

The above specification of my invention signed by me, this 14th day of September, 1867.

ANTONIO L. MORA.
